(57) **CLAIM**

The ornamental design for a vehicle dashboard, as shown and described.

DESCRIPTION

FIG. 1 is a perspective view of a vehicle dashboard, in accordance with the present invention, shown in a condition of use;

FIG. 2 is a front view of the vehicle dashboard of FIG. 1; FIG. 3 is a rear view of the vehicle dashboard of FIGS. 1 and 2;

FIG. 4 is a left side view of the vehicle dashboard of FIGS. 1-3;

FIG. 5 is a right side view of the vehicle dashboard of FIGS. 1-4;

FIG. 6 is a top view of the vehicle dashboard of FIGS. 1-5; and,

FIG. 7 is a bottom view of the vehicle dashboard of FIGS. 1-6.

The broken lines illustrate portions of the vehicle dashboard which form no part of the claimed design. The broken lines showing an instrument panel depict environmental structure which forms no part of the claimed design.

1 Claim, 6 Drawing Sheets
